UNITED STATES PATENT OFFICE.

CARL HORIX, OF CHICAGO, ILLINOIS.

DESIGN FOR A COMBINED RECEPTACLE AND FOUNTAIN-PEN HOLDER.

Application filed April 11, 1927. Serial No. 21,538. Term of patent 14 years.

To all whom it may concern:

Be it known that I, CARL HORIX, a citizen of the United States, residing at Chicago, in the county of Cook and State of Illinois, have invented a new, original, and ornamental Design for a Combined Receptacle and Fountain-Pen Holder, of which the following is a specification, reference being made to the accompanying drawing, forming a part thereof.

In the drawing:

Fig. 1 is a front elevation and Fig. 2 is an end elevation of a combined receptacle and fountain pen holder, showing my new design.

I claim:

The ornamental design for a combined receptacle and fountain pen holder, as shown.

Chicago, Illinois, Apr. 8, 1927.

CARL HORIX.
